Primary Examiner — Leanne Was-Englehart*Assistant Examiner* — Elizabeth S Struble(74) *Attorney, Agent, or Firm* — Daniel M. Cohn; Howard M. Cohn(57) **CLAIM**

The ornamental design for a collapsible foot spa with massager, as shown and described.

DESCRIPTION

FIG. 1 is a top, front, right perspective view of a collapsible foot spa with massager, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, right perspective view of the collapsible foot spa with massager of FIG. 1, shown exploded for clarity of disclosure; and,

FIG. 9 is a top, front, left perspective view of the collapsible foot spa with massager of FIG. 1, shown in a collapsed state for clarity of disclosure.
